CONTROL MEANS

Filed Feb. 23, 1927

Fig. 1

UNITED STATES PATENT OFFICE.

HARRY A. DOUGLAS, OF BRONSON, MICHIGAN.

CONTROL MEANS.

Application filed February 23, 1927. Serial No. 170,189.

My invention relates to means for controlling the ignition of an internal combustion engine, particularly of an automotive vehicle, and the principal object of my invention is to provide new and improved means of this type. In the drawings accompanying this specification and forming a part of this application I have shown, for purposes of illustration, one form which my invention 10 may assume, and in these drawings:

Figure 1 is a view showing this embodiment of my invention as it appears from the dash board of an automobile;

Figure 2 is a section on the line 2—2 of Figure 1; while

Figure 3 is a section on the line 3—3 of Figure 2.

The embodiment of my invention herein disclosed is applied to an ignition coil 11 comprising a secondary 12 and a primary 13 wound about a suitable core 14 and enclosed within a theft-resisting metal tube 15 projecting beyond the two ends of the core 14, containing within one end 39 an insulating bushing 16 insulating that end of the winding 12, and having the other end 40 closed by means of a cap 17 provided centrally with an insulating bushing 18 carrying a contact 19 connected by means of a conductor 20 to one terminal of the secondary 12 and adapted to receive a conductor leading to the distributor, and carrying laterally of the insulating bushing 18 a pair of primary terminals 21 connected by means of conductors 22 to the outer ends of the primary 13 of the coil 11; and the embodiment of my invention herein disclosed comprises a metal cup 23 adapted to be inserted within the relatively open end 39 of the tube 15, and a metal container 24 adapted to be disposed with its edge abutting the edge of the metal cup 23, and the end 39 of the tube 15, and to then have its edge rolled with the edges of the cup 23 and with the end 39 of the tube 15 into a single seam 25 uniting the tube 15 and the cup 23 and the container 24 into a single enclosure; secured together primarily by the seam 25; secured together additionally by a base 26 united to the tube 15 and cup 23 by means of pins 27 extending through the tube 15 and cup 23 into the base 26, and to the container 24 by means of similar pins 28 extending through the container 24 into the base 26; enclosing the ignition coil 11 between the base 26 and the end closure 17; and providing between the base 26 and the front wall 29 of the container

24 a chamber 30 for the reception of control means herein shown as comprising a lock 31 supported in a recess 32 formed by upsetting the central portion of the front 29 of the container 24, held against rotation in any suitable manner as by welding, operable by means of a key 33, and carrying on the rear end of its barrel 34 a switch bar 35 carrying at its ends contacts 36 connected by means of 60 a suitable conductor 37 and adapted to engage cooperating contacts 38 carried by the base 26 and connected by conductors 40 to the two sides of a gap introduced at an intermediate point of the primary winding 13 of the 70 ignition coil 11.

From the above description it will be understood by those skilled in the art that I have provided a unit containing an element essential for the operation of the ignition system, 75 and means controlling this element, mounted in casings adapted to be assembled into a single enclosure enclosing this element and this controlling means and rendering this element inaccessible and inoperable except by the key 80 controlling the lock 31, that with the parts in position permitting the removal of the key and the locking of the switch the circuit through the ignition coil is effectively interrupted, and held interrupted, to be reestablished only by re-insertion of the key, and rotation of the key to bring the parts into the position shown in Figure 2.

Under these circumstances it will be obvious to those skilled in the art that I have provided new and improved control means particularly adapted to the ignition circuit of an internal combustion engine of an automotive vehicle. At the same time, however, it will also be obvious to those skilled in the art that 95 the particular embodiment of my invention herein shown and described may be variously changed and modified without departing from the spirit of my invention, or sacrificing the advantages thereof, and that my invention may be employed other than to control the ignition coil of the ignition system of an internal combustion engine of an automotive vehicle, and accordingly it will be understood that the disclosure herein is illustrative only, and that my invention is not limited thereto.

I claim:

1. In an igniton system for an internal combustion engine of an automotive vehicle, 110 a unit comprising: an element essential in said system for the operation of said engine;

a first theft-resisting casing at least partially enclosing said element; lock-controlled switch means; connections connecting said switch means in controlling relation with said element; and a second theft-resisting casing at least partially enclosing said switch means and united rim to rim with said first theft-resisting casing by a joinder securing said casings into a single enclosure for preventing at least unauthorized access to said switch means and said connections and at least the adjacent portion of said element, at least not without disruption of said unit.

2. In an ignition system for an internal combustion engine of an automotive vehicle, a unit comprising: an element essential in said system for the operation of said engine; a first theft-resisting casing at least partially enclosing said element; lock-controlled switch means; connections connecting said switch means in controlling relation with said element; and a second theft-resisting casing at least partially enclosing said switch means and united rim to rim with said first theft-resisting casing by a rolled seam securing said casings into a single enclosure for preventing at least unauthorized access to said switch means and said connections and at least the adjacent portion of said element, at least not without disruption of said unit.

3. In an ignition system for an internal combustion engine of an automotive vehicle, a unit comprising: the ignition coil of said system; a first theft-resisting casing at least partially enclosing said coil; lock-controlled switch means; connections connecting said switch means in controlling relation with said coil; and a second theft-resisting casing at least partially enclosing said switch means and united rim to rim with said first theft-resisting casing by a joinder securing said casings into a single enclosure for preventing at least unauthorized access to said switch means and said connections and at least the adjacent portion of said coil, at least not without disruption of said unit.

4. In an ignition system for an internal combustion engine of an automotive vehicle, a unit comprising: the ignition coil of said system; a first theft-resisting casing at least partially enclosing said coil; lock-controlled switch means; connections connecting said switch means in controlling relation with said coil; and a second theft-resisting casing at least partially enclosing said switch means and united rim to rim with said first theft-resisting casing by a rolled seam uniting the edges of said casing to secure said casings into a single enclosure for preventing at least unauthorized access to said switch means and said connections and at least the adjacent portion of said coil, at least not without disruption of said unit.

5. In an ignition system for an internal combustion engine of an automotive vehicle,

a unit comprising: a first unitary article of manufacture including, an element essential in said system for the operation of said engine, and a first theft-resisting casing supporting and at least partially enclosing said element; a second unitary article of manufacture including, lock-controlled switch means, and a second theft-resisting casing supporting and at least partially enclosing said switch means; connections connecting said switch means in controlling relation with said element; and means uniting said second theft-resisting casing with said first theft-resisting casing completely enclosing said switch means and said connections and securing said casings into a single enclosure for preventing at least unauthorized access to said switch means and said connections and at least the adjacent portion of said element, at least not without disruption of said unit.

6. In an ignition system for an internal combustion engine of an automotive vehicle, a unit comprising: a first unitary article of manufacture including, the ignition coil of said system, and a first theft-resisting casing supporting and at least partially enclosing said coil; a second unitary article of manufacture including, lock-controlled switch means, and a second theft-resisting casing supporting and at least partially enclosing said switch means; connections connecting said switch means in controlling relation with said coil; and means uniting said second theft-resisting casing with said first theft-resisting casing completely enclosing said switch means and said connections and securing said casings into a single enclosure for preventing at least unauthorized access to said switch means and said connections and at least the adjacent portion of said coil, at least not without disruption of said unit.

7. In an ignition system for an internal combustion engine of an automotive vehicle, a unit comprising: a first unitary article of manufacture including, an element essential in said system for the operation of said engine, and a first theft-resisting casing supporting and at least partially enclosing said element; a second unitary article of manufacture including, a lock-switch, and a second theft-resisting casing supporting and at least partially enclosing said switch; connections connecting said switch in controlling relation with said element; and means uniting said second theft-resisting casing with said first theft-resisting casing completely enclosing said switch and said connections and securing said casings into a single enclosure for preventing at least unauthorized access to said switch and said connections and at least the adjacent portion of said element, at least not without disruption of said unit.

8. In an ignition system for an internal combustion engine of an automotive vehicle, a unit comprising: a first unitary article of

manufacture including, the ignition coil of said system, and a first theft-resisting casing supporting and at least partially enclosing said coil; a second unitary article of manufacture including, a lock-switch, and a second theft-resisting casing supporting and at least partially enclosing said switch; connections connecting said switch in controlling relation with said coil; and means uniting said second theft-resisting casing with said first theft-resisting casing completely enclosing said switch and said connections and securing said casings into a single enclosure for preventing at least unauthorized access to said switch and said connections and at least the adjacent portion of said coil, at least not without disruption of said unit.

9. In an ignition system for an internal combustion engine of an automotive vehicle, a unit comprising: a first unitary article of manufacture including, an element essential in said system for the operation of said engine, and a first theft-resisting casing supporting and at least partially enclosing said element; a second unitary article of manufacture including, lock-controlled switch means, and a second theft-resisting casing supporting and at least partially enclosing said switch means; connections connecting said switch means in controlling relation with said element; and means uniting said second theft-resisting casing with said first theft-resisting casing completely enclosing said switch means and said connections and secur-

ing said casings into a single enclosure for preventing at least unauthorized access to said switch means and said connections and at least the adjacent portion of said element, at least not without disruption of said unit, said second casing being provided with mounting means for said unit.

10. In an ignition system for an internal combustion engine of an automotive vehicle, a unit comprising: a first unitary article of manufacture including, the ignition coil of said system, and a first theft-resisting casing supporting and at least partially enclosing said coil; a second unitary article of manufacture including, lock-controlled switch means, and a second theft-resisting casing supporting and at least partially enclosing said switch means, connections connecting said switch means in controlling relation with said coil; and means uniting said second theft-resisting casing with said first theft-resisting casing completely enclosing said switch means and said connections and securing said casings into a single enclosure for preventing at least unauthorized access to said switch means and said connections and at least the adjacent portion of said coil, at least not without disruption of said unit, said second casing being provided with mounting means for said unit.

In testimony whereof I hereunto affix my signature.

HARRY A. DOUGLAS.

CERTIFICATE OF CORRECTION.

Patent No. 1,708,360.

Granted April 9, 1929, to

HARRY A. DOUGLAS.

It is hereby certified that error appears in the printed specification of the above numbered patent requiring correction as follows: Page 2, lines 57 and 58, claim 4, strike out the words "uniting the edges of said casing to secure" and insert instead the word "securing"; line 115, claim 7, after the compound word lock-switch, strike out the period and insert a comma, and line 129, claim 8, after the word "vehicle" strike out the period and insert a comma; page 3, line 52, claim 10, after the word means, strike out the comma and insert a semicolon; and that the said Letters Patent should be read with these corrections therein that the same may conform to the record of the case in the Patent Office.

Signed and sealed this 21st day of May, A. D. 1929.

M. J. Moore,

Acting Commissioner of Patents.
